UNITED STATES PATENT OFFICE.

ALEXANDER GRAYDON, OF SAN FRANCISCO, CALIFORNIA.

WASHING MACHINE.

Application filed October 18, 1921. Serial No. 508,598.

This invention relates to improvements in washing machines of the type disclosed in my Patent No. 1,437,514, granted December 5, 1922.

5 An object of the present invention is to provide a washing machine of simplified construction having improved means for preventing relative rotation between the suction plunger and the rotatable tub in which it reciprocates.

10 Another object of the invention is to provide improved means for mounting the rotatable false tub which will permit the ready removal of the tub from the machine casing and at the same time prevent the leaking of 15 the washing fluid into the operating mechanism housing.

Other objects of the invention reside in the provision of improved means for the admission of washing fluid into the tub and an 20 overflow drain for the removal of suds and dirt by flushing the tub without opening the main drain line.

Other objects of the invention reside in the 25 more specific and detailed features of construction which will later be described in connection with the illustrative embodiment of the invention shown in the accompanying drawings, in which

30 Fig. 1 is a vertical section of the machine, Fig. 2 is an elevation view,

Fig. 3 is a fragmentary sectional view on the line 3—3 of Fig. 2, and

35 Fig. 4 is a fragmentary sectional view on the line 4—4 of Fig. 2.

Referring to the drawings for a more detailed description, 10 indicates, generally, the machine casing which is divided by an intermediate horizontal partition 11 into an upper 40 compartment or tub 12 and a lower compartment 13 containing the operating mechanism.

That portion of the casing 10 which forms the compartment 13, is formed with perforations 10" which afford proper ventilation 45 for the operating mechanism and motor positioned within this compartment. The operating mechanism is located in a housing or casing 14 supported within the machine casing, as by screws 15 passing through the partition into the adjacent housing wall. The operating mechanism may derive its power from any suitable source, such as an electric motor 16 supported on a platform 17 extending laterally from the housing, and the mechanism is preferably controlled by 50 a gear shifting switch or controlling lever

18 operable from the exterior of the machine casing. The construction and arrangement of the operating mechanism form no part of the present invention. As will be observed, the operating mechanism is entirely enclosed by the housing 14, and the latter is connected with the casing of the machine by means of screws 15; when the screws 15 are removed the operating mechanism will drop. 60

Within the tub 12 is rotatably mounted a false tub 19, preferably provided with perforated walls to permit the admission of washing fluid thereto. The false tub has extending upwardly therethrough from the 70 operating mechanism housing a reciprocable and rotatable shaft 20, adapted to be reciprocated and rotated by the mechanism within the housing 14. The shaft 20 extends through a bearing sleeve 21 having a bottom flange 21' through which pass securing screws 22 connecting the sleeve to the operating mechanism casing. The sleeve has, at its upper end, a stuffing box 23 closed by a cap 24 which serves to prevent the leakage of washing fluid 80 into the operating mechanism housing; and the sleeve is inclosed by a second sleeve 25 bolted at its lower end by screws 26 to the false tub bottom and to a supporting collar 27 surrounding the sleeve 21. The collar 27 is 85 rotatably mounted upon bearings 28, preferably of the ball type, seated within a raceway 29 formed in the top of the operating mechanism housing, and is held against upward movement longitudinally of the sleeve 21 by 90 means of a lock washer 30 surrounding the sleeve 21. The above described mounting for the false tub allows rotation of the tub with a minimum of friction, and at the same time facilitates removal of the tub from the casing 10, it being necessary simply to remove the screws 26 and the outer sleeve 25 in order 95 to withdraw the tub from the casing.

The construction above described serves to 100 prevent washing fluid from seeping into the housing for the operating mechanism. However, should water leak into the housing the same will naturally gravitate to the bottom of the housing, from which it may be removed at intervals by means of a drain tube 14' connecting with one side of the housing adjacent the bottom thereof. This tube extends upwardly and communicates with a valve controlled fitting 14" which is at the 105 normal level of the lubricant in the housing. By operating the valve 14" any water which has seeped into the housing and settled to the

bottom may be removed, since the entrance of the water to the housing raises the lubricant level, and consequently the level of the lubricant being above the plane of the valve 14, water is forced out of the housing through the drain pipe simply by opening the valve. This feature insures a long life for the gears of the operating mechanism, since all washing fluid which tends to thin the lubricant 10 may be removed.

Upon the shaft 20 is mounted a suction plunger 31 which is preferably of substantially the same diameter as the false tub. The plunger is mounted upon a sleeve 31' 15 slidable longitudinally of the shaft 20, and is held upon the sleeve by a lock washer 32. The sleeve is adjustable longitudinally of the shaft and is provided with a locking pin 33 adapted to pass through spaced openings 34 20 in the shaft with which the transverse opening 35 in the collar may be aligned, the desirable adjustment of the plunger along the shaft being dependent upon the amount of clothes within the tub. Manifestly, if the tub is substantially filled with clothes to be 25 washed, it will be necessary to place the plunger at a higher point along the shaft in order to obtain the desired forcing and suction effects than if but a few articles of 30 clothing are to be washed.

It is desirable to prevent relative rotation of the tub 19 and the suction plunger when the tub is rotated to dry the clothes, it having been found that there is a tendency for the 35 clothes to become wrapped around the plunger and shaft and to be torn when such relative rotation takes place. I have found that a preferable construction consists in placing a cover upon the false tub and rotatably 40 securing the cover to the shaft so that the tub may be rotated from the shaft through such a cover. In the illustrated embodiment of the invention the tub 19 is shown as provided with a cover 36 having a depending 45 marginal flange 37 fitting within the tub and frictionally engaging the wall of the latter. The cover is secured to a collar 38 having a reduced portion 38' which rotatably fits within a sleeve 40 upon the machine casing cover 50 10'. The collar 38 is held upon the machine cover by a lock nut 41 threaded upon its end and abutting the end of the sleeve 40.

The collar 38 has a key 42 fitting into a keyway 43 extending along the shaft 20, and, 55 obviously, rotation of the shaft 20 by the operating mechanism will result in a rotation of the false tub 19 through its cover 36. In order to prevent the escape of the washing fluid and suds from the tub through the central opening in the cover 10' during the reciprocation of the shaft and plunger, a cap 44 may be threaded upon the sleeve 40 and such suds as work upwardly through the collar 38 lubricate the upper bearing of the shaft 20. As will be observed, the collar 38

and cap 44 serve to unite the false tub cover 36 and casing cover 10' so that the two covers may be removed as a unit.

Another feature of the invention resides in the provision of means for admitting the washing fluid into the tub 12 without splashing, and for this purpose the tub is provided, upon its exterior (Fig. 2), with a fitting 45 having external nipples 46, 47 to which hot and cold water supply lines may be connected. 75 The admission of washing fluid is controlled by valves 48 which, when opened, permit the fluid to pass through an inlet passage 49 which, it will be observed, is curved in a lateral direction to direct the water in at an 80 angle substantially tangential to the wall of the false tub 19. The inflowing stream of fluid is thus directed around the tub and the force of the same does not strike directly against the wall of the tub. This arrangement permits the admission of washing fluid 85 without splashing, and with every inconsiderable resistance to the inflowing stream.

A drain port 51 at the bottom of the tub permits the draining of the washing fluid 90 from the tub after the washing when it is desired to dry the clothes by rotation of the false tub 19, this port being controlled by a valve 52 which is normally closed and must be opened when the tub is to be drained. 95 However, it is desirable to rinse the clothes before entirely draining the tub in order that the suds and dirt may be thoroughly removed from the clothes and tub, and for this purpose I have provided an overflow device which 100 will permit the opening of the inlet ports for either hot or cold water, or both, and the admission of washing fluid without opening the drain port valve, thereby permitting the flooding of the machine and the removal of all 105 suds, grease and dirt before the drying operation. The valve fitting 52 has a by-pass 53 which communicates, upon the interior of the tub, with an upwardly extending drain passage 54 having an inlet 55 considerably above 110 the bottom of the tub. When the clothes are to be rinsed, preferably before the operation of the plunger is stopped, it is simply necessary to flood the tub by opening the inlet valves 48, and when the water rises above the 115 by-pass inlet 55 the overflow will drain through the passage 54 and by-pass 53. After the rinsing operation is completed the drain port controlling cock 52 may be opened in order to entirely drain the washing fluid from 120 the tub before setting up rotation of the tub in order to dry the clothes. As will be noted from an inspection of Fig. 4 the drain port fitting may have a branch 58 in which is positioned a water gauge 57 extending upwardly 125 through a guide eye 59 in the inlet valve fitting.

It is sometimes found necessary to heat the water within the tub to a higher temperature than the water admitted through the hot 130

water inlet supply line, and for this purpose the drain valve fitting and the inlet fitting may each be provided with an additional port 60 normally closed by a plug 61. When 5 the water within the tub is to be heated a heating coil may be connected at one end to the drain valve fitting at the port 60 and at the other end to the corresponding port in the inlet fitting thus making a thermo-siphon to 10 heat the water.

The operation of this machine will be obvious from the above description and to one skilled in the art, it being understood that the operating mechanism within the housing 14 15 is adjusted by the control arm 18, after the tub 12 has been filled with clothes and washing fluid, to reciprocate the shaft and its suction plunger 31. After this operation has been performed the clothes are thoroughly 20 rinsed to remove the dirt and suds by opening the inlet valves 48 while at the same time maintaining the drain valve 52 closed. This floods the tub and washes the soap and dirt through the over-flow by-pass 54. Subsequently 25 to the rinsing operation the drain valve is opened to remove the water from the false tub and thereupon the operating mechanism is shifted to produce rotation of the shaft 20 and the false tub, which will thoroughly 30 dry the clothes.

It should be understood that the above detailed disclosure is merely illustrative of the invention and in no sense restrictive thereof, numerous modifications being possible within 35 in the scope of mechanical skill and the following claims.

I claim:

1. In a washing machine, the combination 40 of a tub, a false tub rotatably mounted in said tub, a rotatable shaft extending through said tub and having a key-way therein, a removable cover having an opening adapted to be fixedly secured upon said false tub to rotate the latter, the shaft extending through 45 said opening in said cover, a collar on said cover at said opening through which the shaft extends, a key within said collar fitting into the keyway in said shaft, the shaft being reciprocable through said opening, agitating 50 means on said shaft and operating mechanism positioned beneath the said tubs for said shaft.

2. In a washing machine, the combination 55 of a tub, a false tub rotatably mounted in said tub, a rotatable shaft extending through said tubs, a removable cover adapted to be fixedly secured upon said false tub to rotate the latter, the cover having an opening through which the shaft extends, means for establishing 60 a connection between the shaft and cover for rotating the latter by the shaft, the shaft

being reciprocable through said opening, agitating means on said shaft, operating mechanism positioned beneath the said tubs for said shaft, a cover for said first mentioned 65 tub connected to said false tub cover, the latter cover being rotatable relative to the other cover, and the two covers being together removable as a unit.

3. In a washing machine, the combination 70 of a tub, a false tub rotatably mounted in said tub, a cover for said first mentioned tub, a cover for said false tub rotatably connected to the first mentioned cover and removable therewith, a flange on said false tub cover 75 adapted to frictionally engage the wall of said false tub to insure rotation of the latter with its cover, a reciprocable and rotatable shaft extending through said false tub and operatively connected with the cover thereof 80 to rotate the cover, agitating means on said shaft, operating means for said shaft positioned below the tub, and means connecting said false tub cover with the shaft permitting reciprocation of the shaft independent 85 of the cover.

4. In a washing machine, the combination 90 of a tub, a false tub rotatably mounted in said tub, a cover for said first mentioned tub, a cover for said false tub, a flange on said false tub cover rotatably connecting the same with the tub to insure rotation of the tub with its cover, a reciprocable and rotatable shaft in said false tub, agitating means on said shaft, operating means for said shaft below 95 the tub, and means for connecting the shaft to said false tub cover adapted to insure rotation of the cover through said shaft but permitting reciprocation of the shaft relatively to the cover and tub. 100

5. In a washing machine, the combination 105 of a casing having a horizontal partition therein forming a tub thereabove and an operating mechanism compartment therebelow, operating mechanism in said compartment, a false tub rotatably mounted above said partition, a vertically reciprocable rotatable shaft extending upwardly through said partition and said false tub, agitating means on said shaft, a removable cover for 110 said false tub secured to the false tub to rotate the latter, said shaft extending through an opening in the cover, a collar on said cover having a key fitting into a keyway on said shaft, a cover for said casing mounted on said collar, the collar and false tub cover being rotatable relatively to said casing cover, and a stationary cap on said casing cover concealing the collar and shaft. 115

In testimony whereof I have hereunto set 120 my hand.

ALEXANDER GRAYDON.
